Specification for Design.

Patented Nov. 15, 1921.

Application filed October 30, 1919. Serial No. 334,537. Term of patent 7 years.

To all whom it may concern:

Be it known that I, HARRY L. BEACH, a citizen of the United States, residing at Coshocton, in the county of Coshocton and State of Ohio, have invented a new, original, and ornamental Design for Metal Racks, of which the following is a specification.

Referring to the drawing,

The figure is a perspective view of a metal rack, showing my new design.

I claim:

The ornamental design for a metal rack, substantially as shown.

In testimony that I claim the foregoing as my own, I have hereto affixed my signature in the presence of two witnesses.

HARRY L. BEACH.
